FRANK S. HONBERGER, OF LOS ANGELES, CALIFORNIA

PROTECTED CONCRETE PILE

Application filed August 28, 1926. Serial No. 132,074.

This invention has to do with concrete and similar piling or the like; and more particularly with reinforced concrete piling; although the general as well as the particular object of 5 the invention will be best understood from the following detailed description, yet it may be said preliminarily that the general object of the production of a concrete pile or the like that will have immunity or high resistance to the deteriorating action of the water in which it is placed, and at the same time be producible and usable at much lower cost and expense than the concrete pile which has been 10 protected by impregnation or other means throughout its whole length and mass.

Without going into the particulars of causes of concrete pile deterioration, it may be said broadly that most concretes using the average or standard cement deteriorates in 15 sea water or in water containing magnesium sulphate in weak solution. The proposed remedy is to make the concrete of such physical composition as to make it as nearly as possible impervious, or coating it or treating 20 it so as to make it impervious. The making of average concrete impervious has now been proved to be practicable by methods of impregnation hereinafter referred to, and which methods completely seal the concrete against 25 entry of water. It has also been found that in order to prevent deterioration and disintegration of the reinforcing elements in a pile at the points in the pile where the reinforcing elements are alternately subjected to 30 the action of water and air (due to the rising and lowering of water level), the only known practical mode of protection is to completely seal the reinforcements at such points. The zone of greatest reinforcement deterioration 35 has been found to be at or somewhat above the water level. In those parts of a reinforced concrete pile that are submerged and wherein the reinforcements are constantly wet, the deterioration of the reinforcements is very 40 slow. But in those portions where the reinforcements are alternately subjected to action of water and air, or are subjected to the action of moist, and particularly moist salt 45 air, the reinforcement deterioration is comparatively rapid.

It has, therefore, been found that while it is necessary for the complete protection of the upper part of the pile it should be sealed against entry of both moisture and air, and the reinforcements in those parts should 55 therefore be sealed against contact with both moisture and air, yet for the protection of the lower parts of the pile it may be fully sufficient that the concrete need not be rendered impervious to water, but only need be 60 of such composition as to prevent chemical disintegration of the cement itself.

In the issued patents to Frank S. Honberger: No. 1,555,209, dated September 29, 1925, for method of treating concrete, and No. 65 1,555,208, dated September 29, 1925, for method of and apparatus for treating concrete, there are described processes for impregnation of concrete, processes that are particularly applicable to concrete piles and the like 70 and result in their impregnation in such manner as to make the piles fully impervious to both liquids and gases. A reinforced concrete pile thus impregnated (and the impregnation usually permeates throughout the mass of the 75 pile or permeates into the pile to considerable depth below the surface) the reinforcing rods are completely sealed against both moisture and air and are thereby protected from deterioration and disintegration. The impregnating 80 substance most commonly used in the practice of these impregnating processes is asphalt; and the result of the process is to fill completely the interstitial voids of the concrete so that the contained reinforcements 85 are entirely sealed.

It has, however, been found in practice that the total length of piles necessary to reach a suitable footing beneath the water varies quite considerably, whereas the length of piling 90 above the water level is more or less standardized. In any case the length of piling above mean water level is only a somewhat small part of the total pile length; and although it is economically and commercially possible to impregnate the whole length of even the longest pile, it becomes in the case of a pile 100 feet or so in length an operation of some magnitude to handle the pile and to provide impregnating apparatus and chambers of 100

sufficient size. Also, of course, the cost of such impregnation increases more or less directly in proportion to the length of the pile treated.

5 By my invention I provide a pile wherein the upper part is impregnated to render it impervious to moisture and air and wherein the lower part is not necessarily made impervious. Such a pile may be initially manufactured—entirely pre-cast—before placement, or it may be initially made in two parts and those two parts joined together after the lower, or what I may call the water submerged part, is placed. By whatever method the final pile is made, the result in each case is a pile that has high immunity from deterioration and involves only a comparatively short length of impregnating or impervious concrete. The summary result of the invention is thus that a pile of given total length may be produced at considerably lower cost than heretofore.

25 In order that a better understanding of my invention may be had, I will proceed to a more or less detailed description of typical forms of piles that embody the invention, reference for this purpose being had to the accompanying drawings.

30 In the drawings:

Fig. 1 is a vertical longitudinal section of one form of finished pile;

Fig. 2 is a side elevation of the upper part of the pile of Fig. 1;

Fig. 3 is a vertical longitudinal section of another form of finished pile; while—

Fig. 4 is a similar view of yet another form.

Referring first to the form of pile typified in Figs. 1 and 2, and which is the typical form used where the exact depth to which the pile must be driven is not known, I there show a pile composed of a lower section A, an upper section B and an intermediate juncture section C. Sections A and B are pre-cast before the pile is put into place and section C, as will be described, is poured after section A has been put into place and section B is held in place above section A.

50 Section A of the pile may constitute a suitable body of concrete as indicated at 10, equipped with reinforcing rods 11. The concrete in this section of the pile may be, as I have indicated, of any suitable composition to resist chemical action in the water in which the section is submerged. For instance, if the pile is to be used in sea water, it may be composed of concrete, cement and mineral aggregate together with say a suitable percentage of volcanic earth or ash sufficient to take up the free lime in the concrete and thereby prevent reaction between that free lime and the magnesium sulphate in the water. Such compositions for this purpose are known to those skilled in the art and need no detailed statement here.

55 This lower pile section A will initially be

pre-cast of a length preferably greater than the distance to which the pile must be driven below mean low water level. Although it is, of course, possible in some cases to select a length for section A that will bring its finished top end at just the point desired when it has been footed upon the desired foundation, yet in practice this may not always be possible. Accordingly, in the usual practice section A will be driven until it is suitably footed, and then its upper part will be broken off so that its upper end as indicated at 12 in Fig. 1, will then be at the desired height with relation to low water level. Breaking away the concrete of the upper end of the pile will leave exposed the upper projecting ends 11a of its reinforcements, and then if necessary these reinforcements may be cut to their proper projecting lengths and given bends at their upper ends if desired.

60 The upper section B of the pile has been previously pre-cast to the length suitable for the structure that is to be supported. That length will correspond to the height of the structure above mean low water level, and such length is thus one that does not vary greatly for the large majority of pile supported structures.

65 It is, therefore, comparatively easy and economical to pre-cast and impregnate the upper pile section B. In the forms shown in Figs. 1 and 2 this upper section B is cast with a cavity 13 in its lower end and with its reinforcing rods 14 projecting by suitable distance below its lower end as indicated at 14a. After lower section A is driven and its top prepared as previously described, upper section B is then placed in position over lower section A and in about the relation shown in Fig. 1. Then the space between the ends of the two sections is enclosed by a suitable mold or casing 15 and concrete is poured into the enclosed space to fill it and to fill the cavity 13, an opening in upper section B being provided at 16 for this purpose. In the relative positions in which the two sections are placed before pouring of the central joint section C, their two sets of reinforcing rods overlap each other and interlock, as is shown in Fig. 1. Consequently when the joint section C is 70 poured and has set, it becomes in effect an integral part of the two precast sections and the whole pile made of the three sections becomes, in effect, one monolithic and continuously reinforced pile. The form 15 may be either left in place or subsequently removed for further use.

75 Now in a pile thus composed the upper part or section B is formed of impregnated or impervious concrete and, as will readily be seen, its reinforcing rods 14 within that impervious concrete cannot be reached by either moisture or air. In the lower submerged section A the water may have comparatively free entry; and water that enters section A 80

will work up into the joint section C by capillary action so that the interstitial voids of section C are constantly filled with water regardless of the fact that section C is at least 5 at times above the water level. Of course, it will be understood that it is within the scope of my invention that joint section C may be placed low enough as to be always beneath the water level and, therefore, always directly filled with water. But, as I have explained, it may be only necessary to have section C near enough to the water level that the water, by capillary or other action, will keep 10 its interstitial voids filled regardless of the fact that the water level may be somewhat lower. The distance above water level to which section C will be at all times water filled, of course, depends upon the nature of the concrete and upon the sizes and forms of 15 its voids; but whatever that distance is, the completed pile is so designed that the upper part of section C is never at any time high enough above water level that air can ever gain entry to any of its interstitial voids. 20

25 Thus if section C is made of concrete constituted the same as that of section A, it will have the same high resistance to deterioration and reinforcement rods within the joint section C will not be subjected to deterioration 30 and disintegration because they are constantly surrounded by water and never in contact with the air.

In an ordinary pervious concrete pile that has the same pervious constitution throughout its length, the water will rise within the pile and along the reinforcement rods to a certain more or less definite distance above the water level. As the water level rises and falls the water within the concrete correspondingly rises and falls and sets up what may be termed a sort of pumping action within the concrete. Above the highest point reached by the water in the concrete, the reinforcing rods are, of course, constantly exposed to air; 40 below the lowest point reached by the water in the concrete the reinforcement rods are constantly surrounded by water; but between these two points, due to the pumping action of the water up and down, the reinforcement rods are alternately exposed to the action of water and air. Consequently, in a plain pile of that kind, the rods are subject to rapid deterioration throughout their 45 lengths above the lowermost point reached by the water in the concrete.

50 My pile construction not only protects the uppermost parts of the reinforcing rods against air contact, but also eliminate completely in the pile that pumping action that in an ordinary pile subjects the intermediate portion to alternate water and air action. This is true whether the upper section B of the pile be entirely impregnated with asphalt or whether it is only impregnated a suitable 55 depth below its surface. If the entire sec-

tion B has all its interstitial voids filled with impregnating substances, it is, of course, obvious that the water rising in joint section C can only rise to the top of that joint section; and the top of that joint section being always 70 low enough with reference to low water level that section will always be filled with water. Consequently in such a pile the reinforcing rods pass downwardly directly from a space in which they are entirely protected into a 75 space in which they are always surrounded by water, and with no possibility of an intervening space or zone in which they are alternating surrounded by water and air.

These conditions are also true even if the upper pile section B is not entirely impregnated with asphalt or the like. Suppose, for instance, that upper section B is impregnated from its side and end surfaces to a depth sufficient to reach and coat all interstitially exposed surfaces of the reinforcing rods, but leaving what may be called an internal core of unimpregnated concrete, as indicated by dotted lines at 20 in Fig. 1. Although the water rising through section C 80 may, to a certain extent, move up and down in this central unimpregnated core, it cannot reach the reinforcing rods as they are imperviously sealed. Suppose, on the other hand, this central unimpregnated core to be 85 large enough to take in partially or wholly the innermost of the reinforcing rod. The upper end of joint section C being arranged to be always below the lowermost reach of water in the concrete, the water that rises through joint section C will, of course, rise in the lower part of the unimpregnated core of section B. Although the water may work or pump up and down to some extent in this 90 enclosed core, motion up and down is in the first place materially restricted because as the water moves up the air in the core unable to find exit is compressed and as the water moves down the air is rarefied. Consequently the distance through which pumping action 95 takes place is greatly lessened. And although, of course, there will be some deterioration of the reinforcing rods wherever they are in contact either continuously or intermittently with the air, it is obvious that it is 100 always the same air with which they are in contact and that the oxygen of that air will soon be consumed and rusting and further deterioration of the reinforcing rods will be 105 stopped.

110 In Fig. 3 there is shown a somewhat different form that may either be set in place and assembled, as has been described in connection with Figs. 1 and 2, or may be assembled completely before setting of the pile. 115 The distinctive difference between the form of Fig. 3 and that of Fig. 1 is that in Fig. 3 lower section A had been pre-cast to a definite length so that its upper end need not be broken away after setting. It is possible to 120

use such a form as this, or the form shown in Fig. 4, where the depth to which the pile will be driven below water level can be definitely known. Thus the upper end surface 30 of lower section A is here shown as being flat. Upper section B has a cavity 13 into which is poured the joining concrete C-1 to surround and imbed the upwardly projecting reinforcements 11a of lower section A and the downwardly projecting reinforcements 14a of upper section B. It will, of course, be apparent that in using a pile of this form, the several sections may be not only pre-cast, but also formed into a monolithic unitary pile before the pile is set.

15 In Fig. 4 a simpler arrangement is shown for the construction of a pile to be entirely formed before setting. Here the upper section B has no cavity 13, but has its reinforcing rods 14 projecting below its lower end as shown at 14a. The upper section B may be pre-cast and then impregnated and after upper section B is thus finished, the lower section A may be cast into place as illustrated, 20 the concrete of the lower section imbedding the projecting reinforcements 14a of the upper section.

25 These several forms herein illustrated and described typify variations that may be made in the structure of the pile to suit various circumstances. In any case, and whatever the structure may be, it will be seen that the pile embodies the advantageous features hereinbefore set forth; that it has fully the property of self-preservation and at the same 30 time it is much more inexpensively manufactured than is a pile which has to be impregnated throughout its entire length.

I claim:

- 40 1. A concrete pile or the like, comprising two precast and joined sections, the upper section being impregnated with asphalt on all surfaces including the joined surfaces so as to be impervious to fluid entry.
- 45 2. A concrete pile or the like, comprising two precast and joined sections, the lower section having ingredients to resist chemical action upon the concrete by sea water, and the upper section being impregnated with asphalt on all surfaces including the joined surfaces so as to be impervious to fluid entry.
- 50

55 In witness that I claim the foregoing, I have hereunto subscribed my name this 23d day of August, 1926.

FRANK S. HONBERGER
